UNITED STATES PATENT OFFICE.

WILLIAM H. VOSS, OF DAVENPORT, IOWA.

MECHANICAL MOVEMENT FOR WASHING-MACHINES.

No. 892,337.

Specification of Letters Patent.

Patented June 30, 1908.

Application filed October 17, 1906. Serial No. 339,388.

To all whom it may concern:

Be it known that I, WILLIAM H. VOSS, a citizen of the United States, and a resident of Davenport, in the county of Scott and State 5 of Iowa, have invented certain new and useful Improvements in Mechanical Movements for Washing-Machines, of which the following is a clear, full, and exact description.

My invention relates to the actuating 10 mechanism of washing machines, and its object is to provide means for utilizing the momentum of a fly-wheel to assist in actuating a stirrer-shaft driven by a reciprocating lever and particularly the reversing movement of 15 said shaft and thus greatly assist in rendering the manual working of the machine less arduous. This I accomplish by the mechanism hereinafter fully described and as particularly pointed out in the claims.

20 In the drawings:—Figure 1 is a side elevation of a washing machine having my improvements applied thereto. Fig. 2 is a vertical central section thereof taken on dotted line 2—2, Fig. 3. Fig. 3 is a plan view. Fig. 25 4 is a detail view showing the gear connecting the reciprocating lever and stirrer-shaft, on a slightly larger scale.

Referring to the drawings A represents the 30 tub of a washing machine supported at a suitable elevation by legs a, and B represents the cover of the tub hinged, as shown in Fig. 2, to the segmental top piece b that is securely fastened to the upper edge of the tub.

C represents a rotary reciprocal stirrer- 35 shaft, which is journaled in suitable bearings c in the center of the cover B, and has a suitable stirrer-head C' secured on its lower end within the tub. Above its bearings the stirrer-shaft is made square in cross-section and 40 extends up through a pinion D, with which it rotates but can move independently in a longitudinal direction. This stirrer-shaft, after passing through the boss of pinion D, extends up into a suitable sleeve journaled in the vertical bearing e, supported in the upper end of the frame E. Bearing e is of such length that its lower end engages the upper end of the boss of the gear and prevents its displacement from the position shown in the drawings. Projecting laterally from the upper 45 end of the bearing e, is a suitable stud f, upon which is fulcrumed a lever F whose upper portion is provided with a handle of sufficient length, and whose lower portion is formed into 50 a segmental gear g that engages the upwardly

projecting teeth h of a straight horizontally disposed double rack G.

Rack G is provided with a series of laterally projecting teeth j that mesh with gear D, with which it is kept in engagement by means 60 of a squared horizontal guide-bar H, upon which guide-lugs I, I, projecting from the ends of said rack, are slidably mounted. This guide-bar is maintained in about the same horizontal plane as the gear D and rack 65 G, by having its ends secured in short standards k, k, removably secured to the cover, substantially as shown.

At one end the rack G is provided with upwardly projecting pivotal lugs m, between 70 which the adjacent end of a horizontally disposed link J is, preferably, removably secured. This link extends in the same direction as rack G, and has its end farthest from the rack pivotally and adjustably connected to 75 the upper end of a rocking-beam K, which latter is fulcrumed between the lugs of a bracket M, suitably secured to the side of the tub near its bottom. The lower end of beam K extends to a suitable point below the plane of 80 the bottom of the tub, and is connected by a pitman N to the crank-pin of gear O, journaled on a stud projecting laterally from the lower extremity of an L-shaped hanger P, which latter is secured to and depends down 85 from the bottom of the tub. This gear O engages a pinion r on the adjacent end of a horizontal shaft Q, journaled in bearings in the angle or bend of the hanger P, and in bearings R depending from the bottom of the tub near 90 its circumference, and has a suitable fly-wheel T secured to its outer end.

In operation, when the lever F is reciprocated back and forth, the segmental gear g 95 engages and reciprocates rack G, which, through the medium of the pinion D, imparts a rotary reciprocal movement to the stirrer-shaft and stirrer-head. As rack G reciprocates it rocks the beam K, through the medium of the link J, and said beam by means of the pitman N revolves gear O, and the latter drives shaft Q through pinion r, with which it intermeshes. When the shaft Q is 100 revolved the fly-wheel imparts a momentum thereto, which, through the train of the mechanical devices illustrated and described, materially assists in actuating the rack G, and in reversing the same at the ends of the reciprocal throw thereof, and thus lessens the expenditure of physical force, which hereto- 105

fore was demanded of the operator, particularly when reversing the movement of the stirrer-shaft at each end of the reciprocal throw of lever F.

5. What I claim as new is:—

1. A mechanical movement comprising a rotary reciprocal shaft, a reciprocal lever fulcrumed above and adjacent to said shaft, devices through the medium of which the motion of said lever is transmitted to said shaft, a rocking member deriving its motion from said lever at one end, a fly-wheel, and devices connected to the opposite end of said rocking member for actuating said fly-wheel.

15. 2. A mechanical movement comprising a suitable supporting member, a frame mounted thereon, a rotary reciprocal shaft journaled in said frame, a reciprocal lever fulcrumed above and adjacent to said shaft, devices through the medium of which the motion of said lever is transmitted to said shaft, a vertically disposed rocking-beam to which motion is imparted by said lever, a fly-wheel, a shaft for the same journaled below said supporting-member, and devices connected to the lower end of said rocking beam for actuating said fly-wheel.

30. 3. A mechanical movement comprising a suitable supporting member, a frame mounted thereon, a rotary reciprocal shaft journaled in said frame, a gear mounted on said shaft above its journal, a reciprocal rack engaging said gear, a reciprocal lever engaging said rack and fulcrumed in said frame above and adjacent to said rack, a vertically disposed rocking-beam, a link connecting said rack and the upper end of said beam, a fly-wheel, a shaft for the same journaled below said supporting member, and means connecting the lower end of said beam to said shaft.

45. 4. A mechanical movement comprising a suitable supporting member, a frame mounted thereon, a rotary reciprocal shaft journaled in said frame, a gear mounted on said shaft above its journal, a reciprocal rack engaging said gear and having a series of vertically projecting cogs or teeth, a reciprocal lever fulcrumed in said frame and having a segmental gear engaging the vertically projecting teeth on said rack, a fly-wheel, a shaft therefor journaled below said supporting member, and means operatively connecting said rack and fly-wheel.

55. 5. A mechanical movement comprising a suitable supporting member, a frame mounted thereon, a rotary reciprocal shaft journaled in said frame, a gear mounted on said shaft above its journal, a reciprocal rack engaging said gear and having a series of vertically projecting cogs or teeth, a reciprocal lever fulcrumed in said frame and having a segmental gear engaging the vertically projecting teeth on said rack, a fly-wheel, a shaft therefor journaled below said support-

ing member, a pinion on the end of said shaft opposite the fly-wheel, a gear engaging said pinion, and means operatively connecting said lever and gear.

6. A mechanical movement comprising a suitable supporting member, a frame mounted thereon, a rotary reciprocal shaft journaled in said frame, a gear mounted on said shaft above its journal, a reciprocal rack engaging said gear and having a series of vertically projecting cogs or teeth, a reciprocal lever fulcrumed in said frame and having a segmental gear engaging the vertically projecting teeth on said rack, a vertically disposed rocking-beam, a link connecting said rack to the upper end of said beam, a fly-wheel, a shaft therefor journaled below said supporting member, means for operating said fly-wheel, and a pitman connecting the lower end of said beam and said means.

7. A mechanical movement comprising a suitable supporting member, a frame mounted thereon, a rotary reciprocal shaft journaled in said frame, a gear mounted on said shaft above its journal, a reciprocal rack engaging said gear and having a series of vertically projecting cogs or teeth, a reciprocal lever fulcrumed in said frame and having a segmental gear engaging the vertically projecting teeth on said rack, a vertically disposed rocking-beam, a link connecting said rack to the upper end of said beam, a fly-wheel, a shaft therefor journaled below said supporting member, a pinion on the end of said shaft opposite the fly-wheel, a gear engaging said pinion, and a pitman connecting the lower end of said beam and last mentioned gear.

8. A mechanical movement comprising a rotary reciprocal shaft, a reciprocal lever fulcrumed above and adjacent to said shaft, devices through the medium of which the motion of said lever is transmitted to said shaft, a rocking member deriving its motion from said lever at one end, a vertically disposed fly-wheel the axis of the shaft of which is transverse to the axis of said rotary reciprocal shaft, and devices connected to the opposite end of said rocking member for actuating said fly-wheel.

9. A mechanical movement comprising a suitable supporting member, a frame mounted thereon, a rotary reciprocal shaft journaled in said frame, a reciprocal lever fulcrumed above and adjacent to said shaft, devices through the medium of which the motion of said lever is transmitted to said shaft, a vertically disposed rocking-beam to which motion is imparted by said lever, a vertically disposed fly-wheel the axis of the shaft of which is transverse to the axis of said rotary reciprocal shaft, and devices connected to the lower end of said rocking-beam for actuating said fly-wheel.

10. A mechanical movement comprising a

- 5 suitable supporting member, a frame mounted thereon, a rotary reciprocal shaft journaled in said frame, a gear mounted on said shaft above its journal, a reciprocal rack engaging said gear, a reciprocal lever engaging said rack and fulcrumed in said frame above and adjacent to said rack, a vertically disposed rocking-beam, a link connecting said rack and the upper end of said beam, a vertically disposed fly-wheel the axis of the shaft of which is transverse to the axis of said rotary reciprocal shaft, and means connecting the lower end of said beam to said shaft.

10 11. A mechanical movement comprising a suitable supporting member, a frame mounted thereon, a rotary reciprocal shaft journaled in said frame, a gear mounted on said shaft above its journal, a reciprocal rack engaging said gear and having a series of vertically projecting cogs or teeth, a reciprocal lever fulcrumed in said frame and having a segmental gear engaging the vertically projecting teeth on said rack, a vertically disposed fly-wheel the axis of the shaft of which is transverse to the axis of said rotary reciprocal shaft, and means operatively connecting said rack and fly-wheel.

15 12. A mechanical movement comprising a suitable supporting member, a frame mounted thereon, a rotary reciprocal shaft journaled in said frame, a gear mounted on said shaft above its journal, a reciprocal rack engaging said gear and having a series of vertically projecting cogs or teeth, a reciprocal lever fulcrumed in said frame and having a segmental gear engaging the vertically projecting teeth on said rack, a vertically disposed fly-wheel the axis of which is transverse to the axis of said rotary reciprocal shaft, a pinion on the end of said shaft opposite the fly-wheel, a gear engaging said pinion, and a pitman connecting the lower end of said beam and last mentioned gear.

20 13. A mechanical movement comprising a suitable supporting member, a frame mounted thereon, a rotary reciprocal shaft journaled in said frame, a gear mounted on said shaft above its journal, a reciprocal rack engaging said gear and having a series of vertically projecting cogs or teeth, a reciprocal lever fulcrumed in said frame and having a segmental gear engaging the vertically projecting teeth on said rack, a vertically disposed fly-wheel the axis of which is transverse to the axis of said rotary reciprocal shaft, a pitman connected to the lower end of said beam, and means operatively connecting said pitman and fly-wheel.

25 14. A mechanical movement comprising a suitable supporting member, a frame mounted thereon, a rotary reciprocal shaft journaled in said frame, a gear mounted on said shaft above its journal, a reciprocal rack engaging said gear and having a series of vertically projecting cogs or teeth, a reciprocal lever fulcrumed in said frame and having a segmental gear engaging the vertically projecting teeth on said rack, a vertically disposed fly-wheel, a shaft therefor the axis of which is transverse to the axis of said rotary reciprocal shaft, a pinion on the end of said shaft opposite the fly-wheel, a gear engaging said pinion, and a pitman connecting the lower end of said beam and last mentioned gear.
